BY A. M. Pierce,

ATTORNEY.

UNITED STATES PATENT OFFICE.

JOHN J. JACOBS, OF NEW YORK, N. Y.

BUCKLE OR ELASTIC LINK.

969,060.

Specification of Letters Patent. Patented Aug. 30, 1910.

Application filed July 26, 1909. Serial No. 509,671.

To all whom it may concern:

Be it known that I, JOHN J. JACOBS, a citizen of the United States, residing at New York, in the county of New York and State of New York, have invented certain new and useful Improvements in Buckles or Elastic Links, of which the following is a specification, reference being had therein to the accompanying drawing.

10 My invention relates especially to the construction and arrangement of buckles for belts and the like, and has for its object the provision of such buckle, wherein an elastic link is provided which will permit a material variation in the length of the belt while at all times maintaining the requisite tension to keep the belt in proper position.

To attain the desired end, my invention consists in certain novel and useful combinations or arrangements of parts, and peculiarities of construction and operation, all of which will be hereinafter first fully described, and then pointed out in the claims.

In the drawing, Figure 1 is a rear elevation of a belt buckle embodying my invention. Fig. 2 is a like view showing the spring mechanism as partially compressed, permitting elongation of the belt. Fig. 3 is a vertical, sectional view at line *a—a* of Fig. 1. Fig. 4 is a cross-sectional view at line *b—b* of Fig. 1. Fig. 5 is a view of the elastic link removed from the front piece of the buckle. Fig. 6 is a perspective view of a modified form of arrangement of the spring mechanism.

Similar numerals of reference, wherever they occur, indicate corresponding parts in all the figures.

1 is a frame or buckle-front, preferably made of metal.

2 is a back-piece made of leather, or any other appropriate material for closing the opening in the frame 1, but if desired, the front of the buckle may be made entirely of metal.

3 is a cross piece secured to one end of the back of the frame 1. Extending longitudinally of the buckle from the cross piece 3 are guide rods 4.

5 is a yoke for the reception of the clasp of a buckle or any other member it is desired to engage.

6 is a cross bar provided with eyes 7 arranged to engage the bars 4.

8 are spiral springs embracing the rods 4.

9 is a belt, made of leather, webbing, rib-

bon, or any other desirable material, secured to the cross bar 3, passing therefrom around the bar 6, and back beneath the bar 3. By this peculiar arrangement the material 60 9 can lengthen twice the length of the compression of the spring mechanism, as it is secured to the fixed bar 3, and passes around the movable cross-bar 6, over which it plays as the spring mechanism contracts and expands.

When it is desired to use my device to take the place of elastic webbing in suspenders, and the like, the front part of the buckle may be dispensed with, and the rear 70 portion of the mechanism as illustrated in Fig. 5 employed.

The modification of Fig. 6 shows a single spring and guide rod, and such construction does not depart from the spirit of my invention.

My device will be found admirably adapted to the uses and purposes for which it is intended, as it entirely dispenses with elastic webbing, which is liable to rapidly deteriorate with age and use, while possessing all the advantages of such webbing.

Having now fully described my invention, what I claim as new therein, and desire to secure by Letters Patent, is:

1. An elastic link in which is comprised a front portion or frame having an opening, a closing for said opening secured to the back of the frame, a movable bar mounted at the rear of the frame upon suitable guide 80 mechanism which is fixed to the frame, said guide mechanism, belt material secured to the frame at the end opposite to the movable bar and loosely passing around said bar, and spring mechanism engaging said bar and frame, substantially as shown and described.

2. In a device of the character herein specified, the combination with a body or base, of guide-rods fixed to said base, a movable member mounted on said guide rods, 100 springs encircling the guide rods and arranged to engage the movable member, and belt material loosely passing around said movable member, the end of the belt material being secured to the frame, substantially 105 as shown and described.

In testimony whereof I hereto affix my signature in presence of two witnesses.

JOHN J. JACOBS.

Witnesses:

ARTHUR M. PIERCE,
EVA HODGE.
